RAIL JOINT

Lemuel J. Walker, Wauwatosa, Wis., assignor of forty per cent to Albert J. Van Enkvert, Milwaukee, Wis.

Application June 22, 1932. Serial No. 618,729

1 Claim. (Cl. 238—237)

The present invention relates to a rail joint and has for its prime object the provision of an improved joint for the meeting ends of adjacent rails which will provide for a smooth and even passage of the rolling stock over the rails without jar and without subjecting the latter to heavy strains or torsional stresses.

Another important object of the invention resides in the provision of a rail joint of this nature which is comparatively simple in construction, strong and durable, easy to assemble and disassemble, thoroughly efficient and reliable in use and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

Figure 1 is a horizontal section through the joint, and

Figure 2 is a perspective view of the end of one of the rails.

Referring to the drawing in detail it will be seen that numeral 5 denotes a rail base from which rises the usual web 6 and on top of this web is the usual ball 7. The web 6 merges by an angular extension 8 into an offset web extension 9 and it will be noted that the base 5 terminates intermediate the ends of this web extension 9. The ball 7 merges into a ball extension 10 one half the width of the ball 7 and extending along the extension 9 terminating a slight distance from the end of the extension 9 so that said end specifically denoted by the numeral 11 projects beyond the ball extension 10 and is beveled on the inner side thereof for abutting the angular extension 8 and the two rails are assembled as is illustrated to advantage in Figure 1. These web extensions 9 of course, are provided with registering openings 12 so that bolts 14 may be extended therethrough to clamp the extensions 8 securely together. The inner sides of the ball extension 10 are flush with the inner sides of the offset web extensions 9.

It will be also noted that the ball extension 10 adjacent the end 11 of the web extension 9 is beveled as at 10a; and that the web 6 adjacent the angular extension 8 at the right side of the ball extension 10 has its top face beveled as at 7a.

It will thus be seen that when the two rails are assembled the wheels of the locomotive and of the rolling stock will ride only on the ball extensions 10 being entirely out of engagement with the beveled portion 10a, 7a so that a smooth and even passage over the rails at the joint thereof is effected without jar, and without subjecting the latter to heavy strain or torsional

stress and at the same time without the noise now incident to the passage of the rolling stock over rail joints commonly used.

It is thought that the construction, utility and advantages of this invention will now be clearly understood without a more detailed description thereof.

The present embodiment of the invention has been described in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

A rail joint comprising a pair of rail sections each including a base, a web rising therefrom and a ball on top of the web, a reduced extension for each web, the extension of one rail section overlapping the extension of the other rail section, a reduced ball extension for each rail section, the ball extensions of the two rail sections overlapping each other, the free end of each ball extension having its upper face sloping downwardly to the extremity thereof and the end of the wide part of the ball of each section having its top face sloping downwardly to the extremity, said sloping face being located to one side of the point of junction of the ball extension with said ball, whereby said sloping parts form a recess at the point where the free end of a ball extension engages the end of the wide part of the ball, the walls of which are located below the plane of the top part of the ball extension, each web extension being laterally offset from the web, with an oblique part connecting the web extension to the web to provide a vertically arranged sloping shoulder where the inner face of the extension joins the web and each web extension having its free end projecting beyond the free end of the ball extension, with the inner face of said extended end of the web extension sloping outwardly to engage the sloping shoulder of the other rail section.
